UNITED STATES PATENT OFFICE.

JULIUS HAWKINS, OF SEATTLE, WASHINGTON.

COMBINED DAVENPORT AND BED.

1,321,911.

Specification of Letters Patent. Patented Nov. 18, 1919.

Application filed September 25, 1916, Serial No. 121,927. Renewed June 16, 1919. Serial No. 304,723.

To all whom it may concern:

Be it known that I, JULIUS HAWKINS, a citizen of the United States, residing at Seattle, in the county of King and State of Washington, have invented certain new and useful Improvements in Combined Davenports and Beds, of which the following is a specification.

This invention relates to improvements in combined couches or davenports, and folding beds, and has for its object the provision of an article of furniture having the double purpose of normally serving as a couch or settee, and which may be quickly 10 and readily converted into a comfortable bed, all of which functions may be fulfilled without conflict, each form into which the invention is converted affording the full 15 measure of completeness and comfort usual 20 in such form.

A further object of the invention is the provision of a folding bed combined with a couch or davenport, in which the springs and mattress are retracted from view and 25 retained in substantially their normal open position without folding upon themselves, whereby free access of air is admitted to circulate about them with bettered sanitary results.

30 A still further object of the invention is the provision of means whereby the bed portion of the apparatus may be elevated and retained in such position so that the normal height for beds is attained and persons who 35 desire a bed elevated considerably from the floor level may be accommodated.

Other objects of the invention will be indicated throughout the following description of the invention.

40 The invention consists in the novel construction of a davenport and folding bed, and the adaptation and combination thereof, as will be fully described in the following specification, illustrated in the accompanying drawings, and finally set forth in the appended claims.

Referring to said drawings, Figure 1 is a perspective view of a combined davenport and folding bed embodying my invention.

50 Fig. 2 is a cross-sectional view of the same illustrated with the folding-bed portion in operative position.

Fig. 3 is a fragmentary plan view of the bed-frame and springs.

55 Fig. 4 is a cross-sectional view of a detail of the invention.

Figs. 5 and 6 are views in cross-section of a modified form of the invention showing the respective positions of the parts thereof when in use as a bed and as a davenport. 60

Referring to said views, wherein like reference numerals indicate like parts in the several views, the numeral 10 indicates the back wall of a davenport couch, and 11 the side walls or arm members of the same provided with supporting legs 12.

A cushioned back 13 is fixedly secured to said back 10, being supported at its lower end upon a beam 15 longitudinally supported at its ends to said sides 11. A cushioned 70 seat 16 is hingedly connected to said beam 15 and arranged to be swung upwardly when the bed portion of the apparatus is to be utilized.

A skirt board 17 is fixedly connected to 75 the forward edge of said seat 16 to inclose the space therebelow, and affording a pleasing finish to the front of the davenport, as will be more fully described hereinafter.

Said back cushion 13 is spaced from the 80 rear wall 10 to provide a compartment 18 therebetween, and below the seat 16 when in its lowermost position, a compartment 20 is afforded, connecting with said compartment 18. 85

Rigidly mounted on the inner side of walls 11 are guideways 21 extending from close proximity of the forward edge of said walls 11 by suitable direction of its length upwardly toward its rear extremity and terminating in close association with the rear wall 10 within the compartment 18. Said guideways 21 are preferably formed of channeled metal having their respective openings directed toward each other; that is to say, 90 toward the transverse axes of the davenport. 95

The bed frame consists of an inner side bar 22 and an outer side bar 23 that are connected together at their opposite ends by end rails indicated generally by the numeral 25. The outer side bar 23 also serves as a finished front rail for the davenport when the bed is not in use. Said inner side bar and said end rails are preferably of metal and of angle cross-section. Said end 100 rails at their inner extremities where they are supported by the guideways 21 when the bed is in its extended position, and to adapt them to follow the curvature of said guideways, are formed of jointed sections 26 while 110 the outer portion 27 of said rails which projects beyond the davenport walls is rigid.

and is supported in such extended position at its opposite ends by the guideways 21 and auxiliary legs 28 which are rigidly connected to the outer corners of the bed frame.

5 Anti-friction rollers 30 are secured to said end rails at spaced intervals, preferably at the jointed extremities of said sections 26, and adapted to travel in the channel formed in said guideways 21.

10 Bed springs of any suitable design, as 31, are secured to said bed rails, upon which a mattress 32 is supported in the usual manner.

15 Rails 25, being at the head and foot of the bed, receive the major portion of the strain due to the weight of the persons supported on the bed, which stresses are transmitted to a large extent from the end rails 25 to the side rails 22 and 23, but to more positively 20 support the bed frame in symmetrical configuration, the guideways 21 are formed with oppositely disposed flanges 33 (see Fig. 4) against which the rollers 30 may be supported when relatively heavy weights are 25 borne by the springs and transmitted to the end rails.

Normally, the position of the several parts of my described apparatus is as indicated in dotted lines in Fig. 2, wherein the bed frame 30 and mattress are retracted into the compartments 18 and 20, the mattress in such retracted position being indicated by dotted lines 32'. In such position likewise, the seat 16 is lowered, as indicated in dotted lines 35 16', and the apparatus is in its normal daytime condition, wherein it affords a serviceable and attractive article of furniture.

At times when it is desired to use the apparatus as a bed, the seat 16 is elevated, as 40 shown in full lines in Fig. 2, in which position it may be secured by any suitable means, not shown, whereupon the bed frame can be drawn outwardly, the outer end thereof being supported upon the auxiliary legs 28 and 45 the inner end of the end rails including the jointed section 26, and the inner extremity of the section 27, are supported in the guideways 21. Thus a portion of the bed remains within the confines of the side walls 11 and 50 that portion extending into the room beyond said side walls extends only to a relatively small distance, which does not unduly obstruct the room or disorganize its uses for other purposes. It will also be noted that another advantage afforded by the bed made 55 in accordance with my invention, is that when the bed is retracted in its inner inoperative condition, the bed springs and mattress are not folded upon themselves or unduly confined in any way thus preventing 60 thorough ventilation; also it will be obvious that the bed clothing may be spread upon the bed and retained in condition for use without re-making.

65 Referring to Figs. 5 and 6 of my inven-

tion, I have indicated certain added features that may be desirable to accommodate certain persons who may object to sleeping in a bed that is relatively close to the floor.

In this form of my invention, I divide the 70 guide rails, indicated by 21 in the preceding views, into two sections 35 and 36, which may be normally secured together in their alined position by a latch 37 to afford continuous guideways for the rollers 30. 75

Pivots secured at one end to a bottom wall 38 of the couch frame, are spaced parallel bars 40 and 41 which are likewise pivotally secured at their opposite ends in similarly spaced relation to the section 36 in such 80 manner that said section in its lowermost position will be in alined operative connection with the section 35, and thereupon the said parallel bars will lie longitudinally in parallel therewith, as shown in Fig. 6. 85

Upon drawing the bed frame 25 outwardly to bring the rollers 30 past the connection between the sections 35 and 36, the section 36 may be elevated to retain its horizontal position through the well-known action of said parallel bars, and assume substantially the position indicated in Fig. 5. 90

Folding legs 42 are provided at each end of the outwardly extending portion of the bed frame, which may be secured in rigid vertical position by means of a locking brace 43. A locking brace 45 is similarly provided to make rigid connection between the section 36 and one of the parallel bars, as 40, thus retaining the bed in secured position at a 100 suitable elevation above the floor level, to suit the desires or convenience of the user.

What I claim as my invention, is—

1. A davenport-couch having an L-shaped compartment in the lower and back portions thereof, guideways in the opposite ends of said compartment, each composed of two sections one of which is substantially horizontal, a bed frame having flexible end bars adapted to follow said guideways and means to elevate the horizontal sections of said guideways when said bed is extended. 105

2. In a device of the class described, the combination with a davenport couch consisting in a cushion-back having a compartment at its rear, and a hinged cushioned seat having a compartment subjacent thereto, of a pair of curved guideways mounted at opposite ends of said compartments, said guideways each being formed of two sections, a bed-frame formed with end rails each comprised of jointed sections adapted to be retained in and follow the curvature of said guideways, a rigid section adapted to have its inner end supported by said guideways when the bed is in its extended condition, and means to elevate the outermost section of said guideways and said bed-frame in horizontal position. 110

3. The combination with a davenport- 120

couch having a back with a compartment at its rear and a seat with a compartment therebelow, of guideways disposed at opposite ends of said compartments each of said 5 guideways being formed of a substantially horizontal section and a section comprising an upright and a curved portion, a bed frame having jointed sectional end rails, means connected with said end rails and 10 movable within said guideways, means to

elevate the outermost sections of said guideways when said bed is extended and means to secure said sections in elevated position.

Signed at Seattle, Washington, this 20th day of September, 1916.

JULIUS HAWKINS.
